BAG FRAME

Filed July 10, 1926

UNITED STATES PATENT OFFICE.

FRANK T. STUART, OF MAPLEWOOD, NEW JERSEY, ASSIGNOR TO THE R. NEUMANN HARDWARE CO., A CORPORATION OF NEW JERSEY.

BAG FRAME.

Application filed July 10, 1926. Serial No. 121,615.

This invention relates to improvements in traveling bag frames; and the invention has reference, more particularly, to improvements in that type of bag-frame to which the bag-body is secured by sewing.

This invention has for its principal object to provide a novel construction of frame for "sewed-in" bags which is provided with the usual adjuncts comprising a center lock, 10 end latches and handle attachment loops, and which is further provided with a novel construction and arrangement of frame interengaging and supporting elements, in association with said handle attachment 15 loops, adapted to distribute the weight of the bag-body and its content substantially equally relative to both frame members or sections, so that sagging, distortion or other abnormal displacement of one frame member 20 or section relative to the other is prevented.

Other objects of this invention, not at this time more particularly enumerated, will be clearly understood from the following 25 detailed description of the same.

The invention is clearly illustrated in the accompanying drawings, in which:—

Figure 1 is a side elevation of a bag frame made according to and embodying the novel 30 features of this invention; Figure 2 is an enlarged fragmentary longitudinal section of the same; Figure 3 is an enlarged fragmentary bottom plan of the same; Figure 4 is a transverse section, taken on line 4—4 in 35 Figure 2.

Figure 5 is an enlarged fragmentary longitudinal section showing a modified form of frame section interengaging and supporting means; Figure 6 is a bottom plan view 40 of the same; and Figure 7 is a transverse section, taken on line 7—7 in said Figure 5.

Similar characters of reference are employed in all of the hereinabove described views, to indicate corresponding parts.

Referring now to said drawings, the reference characters 7 and 8 respectively indicate the outer and inner frame-sections, with which are respectively connected by brackets

9 and 10, their respective side-frame sections 11 and 12.

Centrally disposed in connection with the outer frame-section 7 is any desired form of center-lock 13 adapted to cooperate with locking elements (not shown) with which the inner frame-section 8 is provided.

Mounted on said outer frame-section 7, so as to be positioned adjacent to the respective ends of the bag-frame, are any desired form of end latch devices 14 adapted to cooperate with the usual keeper tongues (not shown) 60 with which the inner frame section 8 is provided.

Mounted on said outer frame-section 7, so as to be respectively spaced longitudinally from opposite ends of said center lock 13 are handle attachment loops, each comprising a body-member 15 provided intermediate its ends with a transversely disposed upwardly arched portion or loop 16 to form an underlying transverse opening 17 through which the coupling rings at the ends of the usual hand grip or bag handle (not shown) may be engaged in the customary manner. 65 Integrally connected with each end of the body-member 15 so as to project downwardly therefrom, and through perforations in the frame-section 7, provided for their reception, are clinching tongues or lugs 18.

Arranged beneath the outer frame-section 7, in alinement with each handle attachment 80 loop, is a supporting element adapted for interengagement with a cooperating supporting element fixed to the inner frame section 8, so that when said frame-sections are disposed in closed relation, the said inner frame-section is firmly sustained relative to the outer frame-section, and vice versa, thus assuring an equal distribution of the weight 85 of the bag and its content relative to both frame-sections, especially at the point of suspension of the bag by the handle thereof, and consequently preventing either upward bending or distortion of said outer frame-section 7, or downward bending or sagging 90 of said inner frame-section 8, as the case 95 may be.

In Figures 1 to 4 inclusive, I have shown one form of my novel cooperating frame supporting elements, comprising a bridge plate 19 having at its extremities upwardly extending portions 20 from which project outwardly perforate abutments 21 to abut the under side of said frame-section 7, with their perforations matching the perforations of said frame-section 7 through which the clinching tongues or lugs 18 of said handle loop body 15 extend. The bridge plate 19 thus constructed is downwardly off-set or spaced from the under side of said frame-section 7 to provide an intermediate receiving space 22. To secure the bridge plate 19 in the above described relation to the frame-section 7 and the handle loop attachment, the clinching lugs 18 of the latter are passed downwardly through the frame-section and on through the perforate abutments 21 and then clinched over the latter, thus in a simple and economical manner firmly uniting and interrelating such parts. The cooperating supporting element, which is associated with the inner frame-section 8, comprises a bracket member consisting of a vertical portion 23 adapted to abut the outer surface of the side-frame section 12, to which it is firmly secured by a rivet 24, bolt or other suitable fastening means, and a horizontal portion 25 adapted to abut the under surface of the frame-section 8, to which it is firmly secured by a rivet 26 or other suitable fastening. Said vertical and horizontal portions 23 and 25 are integrally connected by an inclined bracket portion 27 which extends across the space between said frame-section 8 and its side-frame section 12, said bracket portion 27 being cut away in its body to provide an opening 28 through which the stitching connecting the bag-body to the frame may be sewn. The free extremity of said horizontal portion 25 is provided with an extension forming a supporting tongue 29 which projects beyond the inner edge of said inner frame-section 8. The relation of these cooperating supporting elements to the inner frame-section 8 is such that the same are disposed for transverse alinement or opposition to the receiving space 22 intermediate the outer frame-section 7 and the bridge plates 19 thereof, and consequently when the frame-sections are closed together, said supporting tongues 29 will enter said receiving spaces above said bridge plates 19 so that any tendency to vertical displacement or bending of either frame-section is obstructed and prevented by the mutual engagement of said supporting tongues and bridge plates one with another.

In Figures 5 to 7 inclusive, I have shown a modified form of my novel cooperating frame supporting elements, which is, however, within the general scope of the present

invention. This modified construction comprises a bridge plate 30 having at its outer longitudinal edge a down-turned flange 31 to abut and be secured to the inner side of the side-frame section 11 of the outer frame 7, by means of rivets 32 or other suitable fastening means. The bridge plates 30 in such form are spaced beneath the outer frame-section 7, in alinement with the respective handle attachment loops, to provide the intermediate receiving spaces 33. The cooperating supporting elements attached to the inner frame-section 7 may be the same in structure as already above described, and as is indicated by the corresponding reference characters applied in said Figures 5 to 7 inclusive. It will be obvious that when the frame-sections are closed together the supporting tongues 29 will enter spaces 33 above the bridge plates 30, so that any tendency to vertical displacement or bending of either frame-section is obstructed and prevented by the mutual engagement of said supporting tongues and bridge plates one with another.

It will be apparent from the above description of my invention, that the frame-sections when closed together will be so mutually interengaged at the points where the weight of the bag is suspended from the bag handle, that all tendency to unequal distribution of such weight to either one or the other of said frame-sections is eliminated, and consequently likelihood of bending, sagging or any abnormal distortion of the bag-frame is prevented.

Having thus described my invention, I claim:

1. In combination with outer and inner frame members of a bag-frame, longitudinally spaced handle attachment loops on said outer member, said handle attachment loops having depending clinching lugs to pass through the body of said outer member, bridge plates having at their ends upwardly off-set perforate abutments to abut the under side of said outer member and through which said clinching lugs of said handle attachment loops also extend, said clinching lugs being clinched over said abutments to thereby rigidly and mutually secure said handle attachment loops and bridge plates in alined relation respectively above and below said outer frame-member with said bridge plates spaced downwardly from the latter, and inwardly projecting supporting tongues rigidly connected with said inner frame member adapted to engage over said bridge plates when said outer and inner frame members are closed together.

2. In a bag-frame comprising an outer member and an inner member adapted to telescope into said outer member, each member having outwardly spaced die-frame sections, and brackets interconnecting said side-

frame sections respectively with said outer and inner sections; a bridge-plate secured to the outer member in downwardly spaced relation to its underside; one of said brackets of said inner member having an inwardly projecting supporting tongue adapted to engage over said bridge-plate when said outer and inner members are closed together, said

latter bracket being cut away at a point intermediate said inner member and its side-frame section to provide a stitching opening therethrough. ¹⁰

In testimony that I claim the invention set forth above I have hereunto set my hand this 6th day of July, 1926.

FRANK T. STUART.
